UNITED STATES PATENT OFFICE.

JOSEPH L. FIRM, OF JERSEY CITY, NEW JERSEY, ASSIGNOR TO THE GOSS PRINTING PRESS COMPANY, OF CHICAGO, ILLINOIS.

PRINTING-PRESS.

SPECIFICATION forming part of Letters Patent No. 556,409, dated March 17, 1896.

Application filed August 17, 1894. Serial No. 520,552. (No model.)

To all whom it may concern:

Be it known that I, JOSEPH L. FIRM, a citizen of the United States, and a resident of Jersey City, in the county of Hudson and State 5 of New Jersey, have invented certain new and useful Improvements in Printing-Presses, of which the following is a specification.

This invention relates to that class of printing-presses known as "rotary web-perfecting," where a plurality of webs are brought together at a given point and carried in a direct line, assembled together, to the longitudinal folding mechanism.

This class of machines to be successful 15 must run at a very high rate of speed, which has a tendency to cause the webs of paper to buckle, stretch or wrinkle, due largely to the unequal tension required to pass the webs between guide-rollers, and the almost impossibility of getting the surface travel of the webs 20 alike to form a correct product. By reducing the distance that each web has to travel from the time its printing is complete until it is associated with the other webs I reduce 25 this tendency to a minimum; and the first part of my invention consists in solving the problem of how to accomplish this result in a printing machine of the class referred to adapted for printing three webs by the arrangement of the cylinders of the three printing mechanisms.

Other parts of my invention embodied in the machine which I am about to describe will be apparent from my description thereof.

35 Figure 1 of the accompanying drawings is a diagram showing in cross-section the arrangement which I prefer for the cylinders and inking mechanisms of the three sets of printing mechanism. Fig. 2 represents the 40 folding mechanism and a side view of the mailing-wrapper attachment. Fig. 3 is an end view of the folding and delivering mechanism. Figs. 4 and 5 are two modifications of the folding mechanism. Fig. 6 is a detail 45 of the delivery mechanism. Fig. 7 is a plan view of the same. Figs. 8, 9, 10 and 11 show the product with the mailing-wrapper in various stages of folding. Figs. 3^a, 12, 13, 14 and 15 are details.

50 In Fig. 1 I have shown the different webs A B C partly unrolled. The web A passes

over rollers 1 and 2 to impression-cylinder D and is printed by form-cylinder E. It then passes over impression-cylinder F and is printed by form-cylinder G on its opposite 55 side. It then passes over the roller 3.

The web B passes over the roller 4 to impression-cylinder H and is printed by form-cylinder I. It then passes over the rollers 5 and 6 to impression-cylinder J and is printed 60 by form-cylinder K on its opposite side. It then passes between the webs A and C between the rollers 3 and 11, or it may pass first over the intermediate roller 7, as shown in dotted line.

65 The web C passes over the roller 8 to impression-cylinder L and is printed by form-cylinder M. It then passes over the rollers 9 and 10 to impression-cylinder N and is printed on its opposite side by form-cylinder 70 O. It then passes over the roller 11, meeting the webs A and B which are passing between the rollers 3 and 11. Thus all the webs form an associated product between rollers 3 and 11. It will be seen by this manner of placing the different form and impression cylinders 75 the web A is brought between the rollers 3 and 11 by the cylinders D E F G, all of one row. The web B is brought between rollers 3 and 11 by using the form and impression cylinders H I of one row and J K of another row, the web C being brought in the same manner by form and impression cylinders L M N O, constituting the remainder of the rows last referred to. By this construction of form and impression cylinders I bring 80 the webs A, B and C together at a given point a minimum distance from the points at which their printing is complete, thereby avoiding chances of the webs deflecting in 85 their travel, buckling, stretching or wrinkling, which is more or less caused by the unequal tension required to pass the webs together between guide-rollers, it being almost impossible to get the surface travel of these 90 webs alike for long distances to form a correct product.

The product of the webs A B C having passed between the rollers 3 and 11 now passes in a straight line to the formers or guiding- 95 frames shown in Figs. 2, *et seq.*

100 Various means may be employed for driving

the cylinders; but I prefer to gear the top row of cylinders together, and the cylinders *c*, *K* and *J* together, and the cylinders *N*, *O* and *d* together, and the cylinders *H*, *I* and *e* together, and the cylinders *f*, *M* and *L* together. Thus the gears *a'* and *a²* connect the cylinder *a* with the cylinder *c*, the gears *b'* and *b²* connect the cylinder *b* with the cylinder *d*, the gears *e'* and *e²* connect the cylinder *K* with the cylinder *e*, and the gears *f'*, *f²* connect the cylinder *O* with the cylinder *f*.

One particular point to which I desire to call attention in the arrangement of cylinders above described is that all of them are arranged in three parallel rows, by which the size of the machine is kept small and the parts are readily accessible. I have shown these rows as in a horizontal position, but I do not wish to be limited to that position. One of the outside rows, which in the illustration happens to be the top row, contains the last cylinder of one printing mechanism, (which is in this case the impression-cylinder *F*,) while the intermediate row contains adjacent to each other the last cylinder of each of the other printing mechanisms, which in the example shown are both impression-cylinders, (*A* and *N*,) though I do not wish to be limited to their being impression-cylinders in contradistinction to form-cylinders.

The last cylinders of all the printing mechanisms are thus brought in close proximity, and by having the assembling-rollers 3 and 11 in the intermediate position shown the distance that the webs pass through between the three printing mechanisms and the assembling-point is reduced to the minimum consistent with the other necessities of the machine. This arrangement likewise enables the inking-cylinders *a*, *b*, *c*, *d*, *e*, and *f* to be disposed at outside points, where they are least objectionable.

The plurality of impression-cylinders *D*, *F*, *J*, and *N* are located at the corners of a polygon, enabling any number to be used as the final cylinders of a plurality of printing mechanisms and enabling the printing of all the webs to be finished at points closely surrounding the guides by which they are assembled, the other rolls of the printing mechanisms being situated at outlying points. In the construction shown there are only three printing mechanisms, and the rolls *D* and *F* are shown as two impression-rolls of one mechanism; but I do not limit myself to that.

It will also be observed that the guiding mechanism—viz., the rolls 3 11 or the rolls 7 3 11—in associating the webs are shown in the drawings as conducting all of said webs through the said polygon; but I do not wish to be limited to conducting all of them through said polygon, since it is only essential, where three web-printing mechanisms are employed, that one should be conducted through the polygon in order to be associated with the other two; or, in other words, that one of the webs should pass from its last impression-cyl-

inder between the last impression-cylinders of two other webs in order to be associated with two other webs.

The webs A B C, having been printed and assembled by the rollers 3 11, pass between rollers 51 52 53 54, are split, and pass down the formers 55 and 155. One half is folded longitudinally by passing between the rollers 56 57, past the tension-roller 58 and between the rollers 59 60. The other half is folded longitudinally by passing between the rollers 156 157, past the tension-roller 158 and between the rollers 159 160. The first half thence proceeds down the former 61, between the rollers 12 13, making the second longitudinal fold while the web is not yet severed. The web then passes between tapes 14 and 15, which pass around rollers 16 13 and 17 18 to the rotary carrier *P*. Then it may receive its transverse fold by passing between the female cutting-cylinder *Q* and the roller 21. The carrier *P* is provided with pins *p*, which impale the forward edge of the web and support it until the line of fold is in the proper position, when a folding-blade *p'* mounted on the carrier *P* will force it between the cylinder *Q* and roll 21 to the grippers on the band 24. The carrier *P* has serrated knives *p²*, which act against the cylinder *Q* to sever the web as it passes between the female cutting-cylinder *G* and roller 21. The cuts from the web pass between the guides 22 23 to the gripper-bands 24, and the grippers 25 25^a 25^b 25^c receive them, thus insuring a positive delivery, and no chance of choking the machine.

Referring to Figs. 12, 13, 14, and 15, the folding-blades *p* and *p'* are shown as mounted in bearings on the carrier *P*. *p³ p⁴* are shafts 105 which have cross-heads *p⁵ p⁶* provided at their ends with pins *p⁷ p⁸ p⁹ p¹⁰*, which pins are guided by fixed cams or templets *p¹¹ p¹²*, connected with the fixed frame *p¹³*, Fig. 15. These cams or templets are so located and 110 formed that the pins on the cross-heads are guided by them. The groove or space between them is lettered *p¹⁴*. Now, as either of the cross-heads is passing around the cam or templet *p¹¹*, it will be held in the position 115 of the cross-head *p⁶*, Fig. 13, and the folding-blade *p'* connected with it will be inactive. When, however, either of the cross-heads reaches the cam or templet *p¹²*, one of its pins will follow the outside surface, as is shown 120 at *p¹⁰*, Fig. 13, and the other pin will pass through the groove *p¹⁴*, as shown at *p⁹*, and one of the folding-blades *p'* will be thrown into action. By turning the templets *p¹¹ p¹²* so that the point of the templet *p¹²* is directed 125 between the rollers *Q* and 21 the paper will be folded between those rollers; but by moving the templets so that the point of the templet *p¹²* is directed between the rollers *u u'* the folding will be done between those rollers. 130 The templets may be adjusted in either of these positions by means of the pin *p¹⁵* by turning the templets so that the pin is inserted either in the hole *p¹⁶* or the hole *p¹⁷*.

The boxes containing the knives in the rollers u' and Q are of ordinary construction, which can be removed when not in action to allow the knives p^2 to pass without cutting the paper.

5 The bands 24 have the four grippers 25 25^b 25^c and are properly timed by the sprocket-wheels 26 and 27 to receive every succeeding folded paper and deliver it to the rollers 28 29 30 31 32 33, which receive their motion through the pins shown on their surfaces from the chain 34, which travels over sprocket-rollers 35 and 36, intermittently actuated by the roller 37 and constantly actuated by the 15 pawl 48.

The sprocket roller or drum 35 is driven as follows: A shaft 43 drives by a worm-gear a counter-shaft 40, which is geared to a disk 47, fixed on the shaft 46 and carrying a spring-pawl 48, which engages with a ratchet-wheel 49 fast on the sleeve 46^a. The sprocket roller or drum 35 is also fast on the sleeve 46^a, and is therefore driven forward by the mechanism just described. On the other end of the 25 shaft 46 are fixed the gears 70 71 72 of different diameters, either of which may be placed in gear with the spur-wheel 73 fixed on the counter-shaft 74. This enables the attendant to control the distribution of the papers 30 on the rollers 28, &c., for convenience of lifting them therefrom.

35 37 is a disk fixed on the counter-shaft 74, which carries a piece of leather 38. Since the disk 37 moves with greater surface speed than the drum 35, every time the leather 38 comes around it will shove the drum 35 ahead of the normal speed received from pawl 48 and thus separate the papers being delivered. The object of this separation is to deliver the 40 papers in one, two, three or four, &c., quires, as may be desired. The rollers 28 to 33 supersede tape belts or aprons with advantage.

The chain 34 besides driving the rollers intersects the path of the sheet as it is carried 45 downward by the band 24 and stops the downward travel of the sheet, so as to direct it on top of the rollers 28 29, &c., instead of permitting it to fall downward in front of roller 28.

When the mailing part of the press is required 50 the female cutting-cylinder R, Fig. 2, will be thrown in gear, giving the required speed to this part of the press. The roll S represents the wrapping mail-paper, which passes between the rollers 80 and 81 to the 55 male cutting-cylinder T, and is cut by the knife t in the groove t' of female cylinder R, and is held on cylinder R in the usual manner by pins t^2 back of the knife-groove. s is the pasting device which pastes the under side 60 of the mail-web on its outside marginal line. (Shown in dotted lines in Fig. 8.) The mailing device is timed to run at the same surface speed as the carrier P, the female cylinder R making two revolutions to the carrier's 65 one.

It is understood that when the mailing-web is introduced the folding-blades $p' p'$ only

work at the top of the carrier R and fold the webs through the rollers $u' u'$, having been cut by the serrated knives p^2 in the female 70 cutting-cylinder Q. The rollers $u' u'$ have tapes 82, 83 and 97. The tape 82 passes over the roller u to male folder U, around it and back over the roller u . The tape 83 on roller u' passes over roller 84 and under 85 75 and around roller 86, back over roller u' . The tape 97 passes around R and u' . It will thus be observed that the front end of the wrapper from the roll S is laid onto the web a short distance back from its front end, as 80 shown in Fig. 8, while the web is still upon the carrier P and before it has been cut transversely. Therefore, the wrapper and the sheet which it is to wrap are brought into contact with each other at or near their forward ends while each still constitutes an unsevered portion of its web, enabling them to be run onto each other with great speed without danger of disarrangement or loss of timing, which might result if either or both were 85 cut from its web before being brought into contact. Moreover, after the front ends are brought into contact the transverse cutting is accomplished by the separate knives t and p^2 before the rear end of the sheet from the 90 wrapper is brought in contact with the web. This enables the wrapper and the web to be cut, so that when brought together the rear end of the wrapper-sheet will overhang the rear end of the web-sheet, as shown in Fig. 100 95 8. The newspaper now receives its first fold transversely by passing between the rollers $u' u$ and tapes 82 83 and is received on carrier or mail-folder U by the gripper 87 and folded by the folding-blade 89, between the 105 rollers 84 and 85. The carrier U has two folding-blades 89 and 90, which work alternately. As each wrapper - web receives its second transverse fold from this carrier, its end being held to the carrier by the grippers 87 or 110 88, which are of the usual construction, the folding-blade 89 or 90 folds it between the rollers 84 and 85 and the tapes 83 and 91. The tape 91 passes over the roller 86, around the 115 third carrier 92, under the roller 94, back and around the roller 85.

The carrier 92 has only one folding-blade 95 and one gripper 96 and makes the last fold between the rollers 86 and 93. It is understood that the same delivery can be used as 120 already described and shown in Figs. 6 and 7.

In Fig. 3 I have shown in detail the two parts of the slit web passing over the formers 55 and 155 to the rollers 56 57 and 156 157, where they meet the tension - rollers 125 58 and 158. The tension is regulated by a swinging bracket 161, which is fulcrumed at 162 to another bracket 163, fulcrumed at 164, the positions of which brackets are controlled by the rods 165 and 166. The webs then 130 pass between the rollers 59 60 and 159 160 to the formers 61 and 167, which are shown at right angles and opposite to each other.

The arrangement shown in Fig. 3, with the

two longitudinal folders in succession, is very important for more than one reason. It leaves space for a person to get at the under part of these longitudinal folders by going between them. The manner of folding the webs by two longitudinal folds before making a transverse fold makes the transverse folder about one-half the size which it would otherwise be, thereby saving the cost in manufacturing and saving space and facilitating the working of these rapid machines.

In Figs. 4 and 5 I show modifications where only three longitudinal folders are required for the two halves of the split webs. The 15 split webs receive one longitudinal fold by the formers 55 155. Then they pass together to the second longitudinal folding mechanism 168, after which they are folded transversely, cut and delivered, as before described.

I claim—

1. In combination, three web-printing mechanisms consisting of form and impression cylinders arranged in three parallel rows, one of 25 the outside rows containing the last cylinder of one printing mechanism and the intermediate row containing adjacent to each other the last cylinder of each of the other printing mechanisms, substantially as described.

2. In a rotary press containing a plurality of web-printing mechanisms, in combination, the final impression-cylinders as F, J and N arranged at the corners of a polygon whereby the points at which the webs leave their respective printing mechanisms are brought close together, and the co-operating form-cylinders of said mechanisms located outside of 35 said polygon, substantially as described.

3. In a rotary press containing more than 40 two web-printing mechanisms, in combination four impression-cylinders as D, F, J and N arranged with their axes at the four corners of a quadrilateral, the form-cylinders located outside of said quadrilateral and guiding 45 mechanism which conducts one or more of said webs through said quadrilateral in associating the same with the others, substantially as described.

4. In a rotary press containing a plurality 50 of web-printing mechanisms, in combination, two printing mechanisms arranged in two rows having their first cylinders, as H, L, at opposite ends of one row and their final cylinders, as J, N, next to each other in another 55 row, and another printing mechanism having its final cylinder, as F, adjacent to said first-mentioned final cylinders, substantially as described.

5. In combination, three web-printing mechanisms consisting of form and impression cylinders arranged in three parallel rows, one of 60 the outside rows containing the last cylinder of one printing mechanism and the intermediate row containing adjacent to each other, the last cylinder of each of the other printing mechanisms, and guide-rollers interposed between the rows containing said last cylinders

whereby the webs may be assembled between said rows and directed to the folding mechanism, substantially as described.

6. In combination, three web-printing mechanisms consisting of form and impression cylinders arranged in three parallel rows, one of the outside rows containing, in the middle, the two impression-cylinders of one printing 75 mechanism and the intermediate row containing opposite said two impression-cylinders the two last cylinders of the other two printing mechanisms, substantially as described.

7. In combination, a rotary printing mechanism, a carrier whereon the page-web is received after being printed, mechanism whereby a sheet is cut transversely from said page-web, mechanism whereby a wrapper-web is run onto said page-web while upon said carrier, mechanism whereby the wrapper-web is cut transversely so that the wrapper-sheet 85 overhangs the page-sheet at the end and mechanism whereby the page-sheet and wrapper-sheet are folded together, substantially as described.

8. In combination, a rotary printing mechanism, a carrier whereon the web is received after being printed, mechanism whereby the front end of a wrapper is laid onto the web 95 while upon said carrier, mechanism whereby a sheet is cut transversely from said web while upon said carrier before the rear end of said wrapper is laid onto the same and mechanism whereby the sheet and the wrapper are folded 100 together, substantially as described.

9. In combination, a rotary printing mechanism, a carrier whereon the web is received after being printed, mechanism whereby the front end of a wrapper is laid onto said web 105 while upon said carrier, mechanisms whereby sheets are cut from said web and said wrapper while their forward portions are together but their rear portions are separate and mechanism whereby the sheet and the wrapper are 110 folded together, substantially as described.

10. In a perfecting-press, in combination, the driven shaft 46, a disk fast on the same, a pawl on said disk, a sleeve on said shaft, a ratchet-wheel fixed on the sleeve, the drum of 115 the delivery mechanism fixed on said sleeve, a counter-shaft, means for driving said counter-shaft from said first-named shaft, and a member on said counter-shaft engaging intermittently with said drum to produce a variable 120 motion thereof, substantially as described.

11. In combination, a rotary printing mechanism, a carrier whereon the web is received after being printed, mechanism whereby a wrapper extending toward the forward end of 125 the web within half the length of a sheet is laid onto the web while upon said carrier, mechanism whereby a sheet is cut transversely from said web and mechanism whereby said sheet and said wrapper are twice transversely folded together whereby one end of the wrapper is caused to extend between the folds of the sheets, substantially as described.

12. In combination, longitudinally-folding

mechanism, a carrier onto which the longitudinally-folded web passes, folding-rollers adjacent to the periphery of said carrier, a folding-blade mounted on said carrier so as to 5 fold the paper transversely between said rollers,

a transverse cutter mounted on said carrier and cutting against one of said folding-rollers and a gripper-carrier whereby the folded edge is gripped while still extending 10 between said folding-rollers and onto said carrier and while still joined to the web, whereby the sheet is positively controlled, substantially as described.

13. In a rotary press containing a plurality 15 of web-printing mechanisms, in combination, the final-impression cylinders as F, J and N arranged at the corners of a polygon whereby the points at which the webs leave their respective mechanisms are brought close together, guiding mechanism which conducts one or more of said webs through said polygon in associating it with the others and the co-operating form-cylinders of said printing mechanisms located outside of said polygon, 20 substantially as described.

14. In combination, a rotary carrier P, a folding-blade carried thereby, rollers through which the paper is folded by said blade, a gripper-carrier receiving the paper from said 25 folding-rollers and a delivery mechanism con-

taining a series of supporting-rollers placed side by side and mechanism whereby said rollers are driven, and a carrier as 34 whereby the paper is directed on top of said rollers substantially as described.

35

15. In a perfecting-press, in combination with the form-cylinders whereby pages are printed on a web abreast, the longitudinal folder whereby the web is folded on the longitudinal margin, a rotary carrier, a holder 40 on said carrier for holding the forward end of the web, a knife on said carrier for cutting the web transversely between succeeding pages, folding-rollers Q and 21 of smaller diameter than a carrier, the opening between 45 which is substantially radial to the carrier and one of which folding-rollers is of a circumference divisible into the circumference of the carrier and carries the female member to co-operate with said knife a folding-blade 50 on said carrier and mechanism whereby said blade is thrust between said rollers when said carrier has advanced substantially half the distance between said holder and said knife, substantially as described.

JOSEPH L. FIRM.
